UNITED STATES PATENT OFFICE.

EUGENE HUBBELL, OF ST. PAUL, MINNESOTA.

DESIGN FOR A RECTAL DILATOR.

SPECIFICATION forming part of Design No. 24,547, dated August 13, 1895.

Application filed March 25, 1895. Serial No. 543,160. Term of patent 14 years.

To all whom it may concern:

Be it known that I, EUGENE HUBBELL, a citizen of the United States, residing at St. Paul, in the county of Ramsey, State of Minnesota, have invented and produced a new and original Design for a Rectal Dilator, of which the following is a specification, reference being had to the accompanying drawings, forming part thereof.

Figure 1 is a plan view showing my design. Fig. 2 is a sectional view of the bulging portion of the larger end of the design. Fig. 3 is a similar view of the smaller end.

The leading feature of my design is its peculiar shape, having obtusely-pointed ends, slightly bulged near the extreme end and one

end being larger than the other, and the walls of the device upon either side of a central rib or ring being contracted, whereby the device is of less diameter at these points, respectively, than at the bulging portions, near its opposite ends. 20

I claim as my invention—

The design for a rectal dilator, substantially as shown and described. 25

In testimony whereof I have hereunto set my hand this 2d day of January, A. D. 1895.

EUGENE HUBBELL.

In presence of—

C. G. HAWLEY,
F. S. LYON.
